UNITED STATES PATENT OFFICE.

EMILE BOURDELLES, OF PARIS, FRANCE.

WHEELED GUN-CARRIAGE.

1,112,430.

Specification of Letters Patent.

Patented Oct. 6, 1914.

Original application filed May 21, 1913, Serial No. 768,953. Divided and this application filed April 20, 1914. Serial No. 833,946.

To all whom it may concern:

Be it known that I, EMILE BOURDELLES, a citizen of the Republic of France, and resident of Paris, France, have invented a new 5 and useful Improvement in Wheeled Gun-Carriages, which invention is fully set forth in the following specification.

This invention relates to wheeled gun carriages, and more particularly to such carriages when provided with a supporting frame for the gun pivotally mounted on the axle of the carriage and with rearwardly extending anchor members, the free ends of which rest on the ground.

15 The invention herein set forth is divided out of my pending application Serial No. 768,953, filed May 21, 1913.

This invention has for its object to provide a wheeled gun carriage in which the 20 strains of recoil shall be transmitted directly through the anchor members to the axle and the wheels without the interposition of any connecting pivots which might form a source of weakness, and at the same 25 time leave such anchor members free to adapt themselves to the conformation of the ground on which the gun carriage may rest.

With this object in view, the invention 30 consists in providing a gun carriage with anchor members, preferably diverging toward the rear, which members are mounted to turn on the axle itself as a pivot, said members being connected to each other by means of suitable gearing whereby they 35 may be simultaneously turned about the axle, but in opposite directions, and thus adjust themselves to the conformation of the ground on which the carriage rests.

In order that the invention may be readily 40 understood, reference is had to the accompanying drawings showing one constructional form thereof, in which—

Figure 1 is a plan view of a wheeled gun carriage embodying my improvement; and 45 Fig. 2 is a vertical sectional detail view taken on the line 2—2 of Fig. 1.

In the drawings are shown a pair of wheels and axle of a gun carriage, on the axle *b* of which are hinged two anchor 50 members *a* hinged on the carriage axle by means of sleeves *a'* formed in the forward ends of the members and held against side-wise movement on the axle between shoulders *c* and nuts *d*. The forward ends of the 55 anchor members *a* are provided with gear

teeth *k* which mesh with a toothed connecting member *h* pivotally mounted on the forward side of the axle *b*. This pivoted member is held in place by a lock nut *e*. The top gun carriage, not shown, is supported 60 on a pivot *g* preferably carried by the axle *b*.

The operation of the device will be readily understood from the preceding description. The anchor members *a* are free to 65 swing in planes transverse to the gun carriage axle, while their free ends are constrained to move simultaneously by reason of the gear connection but in opposite directions, thereby enabling the anchor members to adapt their position to any conformation 70 of the ground independently of the ground support on which the wheels may happen to rest. By this arrangement the recoil strains are directly transmitted to the axle and 75 wheels without the interposition of any pivots which might form a source of weakness.

What is claimed is:—

1. In a gun carriage, the combination with the axle of the carriage, of a pair of 80 anchor members provided with gear teeth and revolvably supported on said axle, and a rotary member mounted on said axle having gear teeth engaging said teeth on the anchor members.

2. In a gun carriage, the combination with the axle of the carriage, of a pair of anchor members revolvably mounted on said axle and having forwardly extending ends 90 provided with gear teeth, and a member pivoted to said axle between said members and having teeth engaging the teeth on said anchor members for causing said members to rotate together.

3. In a gun carriage, the combination of 95 the axle, a pair of anchor members mounted on opposite sides of the center of the axle and turning on the axle as a pivot, and gearing directly connecting said anchor members whereby they may be simultaneously 100 turned independently of the axle.

4. In a gun carriage, the combination with the axle of the carriage, of a pair of diverging anchor members mounted to turn 105 on the axle as an axis, said anchor members having their portions to the rear of the axle resting on the ground and with portions extending forwardly of the axle, and gearing connections between the forward portions of said anchor members.

5. In a gun carriage, the combination with the axle of the carriage, of a pivot extending forwardly of the axle in the horizontal plane thereof, a member mounted to turn on said pivot and having gear teeth on opposite sides of said pivot, and anchor members mounted to turn on the axle of the carriage as an axis and having forwardly projecting arms provided with gear teeth

engaging the gear teeth on said pivoted member.

In testimony whereof I have signed this specification in the presence of two subscribing witnesses.

EMILE BOURDELLES.
